UNITED STATES PATENT OFFICE.

SAMUEL ALBERT GUTTERIDGE, OF LONDON, ENGLAND, ASSIGNOR TO THE AMALGAMATED DENTAL COMPANY LIMITED, OF LONDON, ENGLAND, A BRITISH COMPANY.

DENTAL APPARATUS.

Application filed May 26, 1925, Serial No. 32,958, and in Great Britain June 11, 1924.

This invention consists in improvements in or relating to dental apparatus and has reference to that type of apparatus employed in charging flasks with rubber or like material from which an artificial denture is to be prepared. In charging flasks by injection under pressure, it is necessary that the rubber or rubber composition or the material used for the denture, be heated sufficiently 10 to bring it into a plastic or semi-fluid condition in which it can be forced into the mould-cavity in the flask so as to fill that cavity. Not only must the charging cylinder in such a device be maintained in a heated condition, but it is also necessary to heat the flask itself during the process.

According to the present invention, charging apparatus for the above purpose comprises in combination a heating container, 20 a jacketing wall wholly or mainly surrounding it, a jacketing passage extending through adjacent container and jacket walls for the reception of a charging cylinder, and means permitting communication between the interiors of the jacket for the said passage and that surrounding the container. Thus, heating fluid in the jacket surrounding the container can pass into the jacketed passage so that both the interior of the charging cylinder and the interior of the container can 30 be maintained at the required temperature.

Preferably a conduit is led to the interior of the container from the jacket-space surrounding it, so that if required, steam or 35 heating fluid from the jacket-space can be passed into the interior of the container to increase the temperature therein.

In a preferred construction of apparatus, 40 a charging cylinder has a charging plunger to co-operate therewith, and the plunger is carried in a bracket which is so operatively connected with the charging cylinder that end pressure exerted by the plunger is not applied directly to the walls of the container 45 or its jacket. Conveniently the bracket is secured, by means of a pivotal connection, to the jacket of the passageway which receives the charging cylinder, the pivotal axis being transverse to the throughway length 50 of the passageway. Thus, when the plunger is retracted so as to be clear of the cylinder it can be swung round to one side while supported in the bracket.

In order that the invention may be more clearly understood, one construction of apparatus will now be described by way of example only with the aid of the accompanying drawing in which:—

Figure 1 is a central sectional elevation of the apparatus; and

Figure 2 is a plan of the apparatus shown in Figure 1 with the lid or cover of the container removed.

Like reference numerals indicate like parts in both figures of the drawings.

The container 10 may be of copper or other metal and is enclosed in a jacket 11 so that the container is suspended from the top of the jacket and has a clear water space beneath it and round its lateral walls.

Passing through the walls of both the container and the jacket is a sleeve 12 formed with perforations 13 which communicate with the space between the jacket and the container. Mounted on the end 70 of the sleeve 12 to swing about the pivots 14 is a bracket 15 in which a charging plunger 16 is carried. The charging plunger is rotatably mounted on the end of a screw 17 which is threaded through a boss on the 75 bracket 15.

The sleeve 12 is provided with a liner 18 so as to provide a tubular water jacket within which a charging cylinder 19 is slidably received. The liner 18 may be brazed or otherwise secured to the sleeve 12 and the latter is made a fluid-tight fit with the walls of the jacket 11 and the container 10 by brazing, sweating or other preferred means. A split ring 20, received in a groove in the 80 sleeve 12, affords a stop to engage a shoulder 21 formed as an extension of the container 10 to resist the pressure tending to withdraw the sleeve 12 to the right of Figure 1 during the charging operation. The split 85 ring 20 thus reinforces the means by which the sleeve is secured to the wall of the container 10.

It will be seen that the end pressure exerted by the plunger during the charging 100 operation is exerted primarily on the pivotal connection between the bracket 15 and the sleeve 12 and such pressure as is exerted on the wall of the container 10 is distributed over the area of connection between the 105 sleeve 12 and that wall. It will also be seen

that by provision of the pivotal connection of the bracket the latter, with the plunger, can be swung round to one side so as to leave the entrance to the charging cylinder 19 quite clear.

Extending through the container and the jacket walls at a position diametrically opposed to the charging cylinder is an adjustable back stop 22 in the form of a threaded

10 rod which is engaged with a screw-threaded inner end of a sleeve 23. The sleeve passes right through both the jacket and container walls and its joints with those walls are made fluid-tight in a manner similar to that

15 in which the sleeve 12 is also made fluid-tight with those walls. Also a split ring 24 is provided to serve a similar purpose to that of the split ring 20, above described.

20 A flask 25, in which the mould cavity and teeth are indicated, is shown in the position which it will occupy during the charging operation. The outlet nozzle of the charging cylinder 19 is shown in engagement with the inlet to the flask which latter may be constructed conveniently in the manner described in co-pending application Serial No. 32,957, filed May 26, 1925. The back stop 22 is then screwed up to hold the inlet opening of the flask tight up against the outlet nozzle of the charging cylinder and the latter is prevented from movement by set screws 36 which pass through a flange (forming part of the charging cylinder) and which screw into the end of the sleeve 12.

Assuming that a wax model has been invested in plaster in the flask 25 and the wax has been removed in any preferred manner the mould thus provided is in communication with the inlet opening in the flask. Water contained in the jacketed space surrounding the container 10 is heated up by means of a burner placed beneath the jacket; the bracket 15 is swung aside and a charge of rubber is inserted into the charging cylinder 19 and the bracket is thereafter swung back so that the plunger may be screwed so as to enter the end of the charging cylinder. As nearly the whole length of the charging cylinder is surrounded by the jacket afforded by the sleeve 12 and liner 18, hot water from the jacketed space surrounding the container 10 will enter through the orifices 13 and heat up the rubber charge within the charging cylinder. When the rubber is sufficiently plastic the plunger 16 is gradually screwed up to force the charge into the mould until the latter is entirely filled whereupon inlet and outlet openings in the mould can be closed, for example, by means of a slide 26 such as is described in the co-pending application above referred to. A lid 27 can be used to close the open end of the container 10.

If it is desired to heat the flask more in-

tensely than it will be heated merely by radiation from the walls of the container 10, steam or water may be admitted from the jacketed space enclosed by the jacket 11 through a pipe 28 opening at 29 into the 70 interior of the container 10 near the base of the flask 25. The passage through the tube pipe 28 is controlled by means of a cock 30.

A safety valve 31 is conveniently provided 75 and in the cap 32 which normally closes the filling opening for the jacket 11 there is preferably provided also a second safety valve 33.

To the jacket 11 there may be secured 80 legs 34; or the latter may be secured to a ring 35 forming a support on which the jacket 11 may rest. The height of the legs 34 is chosen to conform to the particular heating appliance which is to be used. 85

The sleeve 12 with its liner 18, bracket 15, plunger 16, and rod 17 are formed as a separate unit apart from the container 10 and jacket 11 and the invention includes 90 such a unit for use in apparatus of the type described herein.

The invention is not limited to the particular constructional details described as these may be varied without departing from 95 the invention.

I claim:—

1. Charging apparatus for the purpose described comprising in combination a heating container, a jacketing wall for the same, and a jacketed passage extending through adjacent container and jacket walls for the reception of a charging cylinder, the interior of the jacket of which passage is in open communication with the interior of the jacket of said container, substantially 100 as described.

2. Charging apparatus for the purpose described comprising in combination a heating container, a jacketing wall for the same, a jacketed passage extending through adjacent container and jacket walls for the reception of a charging cylinder, the interior of the jacket of which passage is in open communication with the interior of the jacket of said container, and a conduit connecting the jacket space of the container with the interior of the container for conveying heated fluid from the container jacket into the container, substantially 110 as described.

3. Charging apparatus for the purpose described comprising in combination a heating container, a jacketing wall for the same, a jacketed passage extending through adjacent container and jacket walls, a charging cylinder in said passage, a charging plunger for co-operating with said cylinder, and a bracket in which said plunger is mounted, which bracket is so operatively 115 engaged with the charging cylinder that the 120

walls of the container and its bracket are relieved of end pressure applied by the plunger to the cylinder, substantially as described.

5 4. Charging apparatus for the purpose described comprising in combination a heating container, a jacketing wall for the same, and a jacketed passage extending through adjacent container and jacket walls, the interior of the jacket of which passage is 10 in open communication with the interior of the jacket of said container, a charging cylinder in said passage, a charging plunger for co-operating with said cylinder, and a 15 bracket that is mounted on the jacket of

said passage and carries said plunger, substantially as described.

5. In charging apparatus of the kind described, an unitary structure comprising the combination of a jacketed holder for 20 use with a jacketed heating container, a charging cylinder carried in said holder, a plunger for the charging cylinder, and a guide bracket that carries said plunger and is mounted on said jacketed holder, substantially as described. 25

In testimony whereof I affix my signature.

SAMUEL ALBERT GUTTERIDGE.
